(57) **CLAIM**

The ornamental design for a bagged ice dispensing machine, as shown and described.

DESCRIPTION

The FIGURE is a top-left-front perspective view of a bagged ice dispensing machine showing my new design, according to an embodiment.

The broken lines in the FIGURE show portions of the bagged ice dispensing machine that form no part of the claimed design.

All other perspective views, and all orthogonal views, of the bagged ice dispensing machine are not shown and form no part of the claimed design. Any surface, or any portion of any surface, of the bagged ice dispensing machine not shown in the FIGURE forms no part of the claimed design.
